SHOE PLATE

Abraham Schemel, Yonkers, N. Y.

Application April 27, 1935, Serial No. 18,610

6 Claims. (Cl. 36—59)

Among the principal objects which the present invention has in view are: To provide a plate for a shoe whereby spikes or the like may be readily locked thereto; to provide means to prevent clogging of the openings in the plate when spikes are detached; to enable a user to readily disassemble the spikes from the plate; to provide means whereby a user will not suffer any discomfort when wearing a shoe having the plate with spikes attached thereto; to provide locking means to hold the spikes to the plate and prevent accidental disengagement of the spikes therefrom; to present spikes having reinforcement at points of contact to insure long wear; to present a combination plate with spikes adaptable for easy attachment to shoes; and to obtain other advantages and results as may be brought out in the following description.

Drawings

Figure 1 is a bottom plan of a shoe showing the combination plate and spikes thereon in place; Figure 2 is a view similar to Figure 1 and showing the spike removed therefrom; Figure 3 is an enlarged plan of the combination plate and spike removed from a shoe; Figure 4 is a longitudinal sectional view shown as taken on line 4—4 of Figure 3; Figure 5 is a similar view and showing the same in disassembled condition; Figure 6 is a transverse sectional view shown as taken on line 6—6 of Figure 3; Figures 7 and 8 are similar views showing the same in locked and open positions as taken on line 7—7 of Figure 3; Figure 9 is an enlarged end view of a spike and showing the attaching means thereon for holding the same to the plate;

Figure 10 is a sectional view of the same as taken on line 10—10 in Figure 9; Figure 11 is a view similar to Figures 4 and 5 with slightly modified constructions;

Figure 12 is a bottom plan and showing a further modification of plate and spike attached 45 to a shoe; and

Figures 13 and 14 are sectional views taken on lines 13—13 and 14—14 respectively of Figure 12.

Description

As seen in the drawings and referring more particularly to Figures 1 to 11 inclusive, I have shown the bottom of a shoe 15 having a heel 16 and sole 17, the construction of which may be 55 of the usual type such as used by players in

various fields of sports, for instance, runners, football players, baseball players and so forth, who at times find it very inconvenient and injurious to keep wearing their shoes with spikes and/or the like when not actually engaged in 5 the game or competition. Heretofore users of spiked shoes have had to change their shoes or walk on the spikes. According to the present invention it will not be necessary for a wearer to remove the spiked shoes when not engaged in 10 competition, but instead the user keeps the shoes on and may easily remove the spikes and/or the like at will therefrom. Furthermore, according to my invention I can provide a shoe with spikes 15 selectively upon the ball of the foot, the heel or both, securely retained in place to heel and sole plates in the shoe 15.

In carrying out the present invention, I provide a metal attaching plate 18 to remain a part of the shoe 15 with the body portion of said plate preferably having the shape of a standard spike plate 19 and embedded flush with the bottom of the shoe. Entirely embedded within the bottom of the shoe is another plate 20, for convenience referred to as a base plate, and which is preferably flat. Rivets 21 or other suitable means applied at the corners of the attaching plate 18 will secure the two plates permanently assembled. The body portion of attaching plate 18, however, is offset from the base plate 20, 30 this being conveniently accomplished by offsetting each corner 22 of the attaching plate. The outer ply, sole or lift of the shoe bottom is provided with an opening shaped to fit around the body portion of the attaching plate and overlie 35 the offset portions thereof and the edge portions of the base plate. After this assembly of plates is applied to said ply, sole or lift, stitching or otherwise securing the ply, sole or lift makes the plates a permanent and solid part of the 40 shoe but without protruding from the bottom. This operation will assure at all times a permanent fixture of the plates 18 and 20 either to the sole 17 or heel 16 of the shoe 15. In passing it is to be noted that the base plate 20 in shape 45 is substantially the same as that of the sole portion of the shoe, though somewhat smaller in contour so as not to interfere with the stitching operation when the ply, sole or lift is stitched or otherwise attached to the welt of the shoe. 50 I have found it very advantageous to utilize the base plate 20 in connection with the present invention for several reasons, one of said reasons and a particular feature being that it will prevent concentrated pressure of the spikes, when 55

worn, bearing against the underside of a person's foot.

By virtue of the off-set mounting of the body of attaching plate 18 and base plate 20, a hollow space or recess 24 is provided, the purpose of which will hereinafter be more fully described.

The attaching plate 18 is conveniently provided with a plurality of openings therethrough, said openings preferably being in the form of open-ended or key-slots 25, one of which is adjacent the forward end of the base plate and two others toward the rear of the plate, all substantially directed longitudinally of the shoe with their larger or open ends similarly placed with respect to each other. Two of these slots are equally spaced from the toe and symmetrically disposed with respect to a medial line longitudinally of the sole, and between them is provided an opening 26 which likewise penetrates the thickness of the attaching plate 18.

Centrally of the plate 18 and in line with the opening 26 and the one key-slot 25 adjacent the forward end of the plate is a rivet 27 passing therethrough from the inner side of the plate 25 and adjacent the underside of the base plate 20. Said rivet 27 securely holds a member 28 in place to the inner surface of the plate 18, said member being of relatively thin spring metal and normally juxtaposed against the inner surface 30 of said plate, and preferably having an area sufficient to underlie and close all said openings 25 and opening 26, thereby preventing dirt or other foreign substance from entering through these holes to fill the recess 24 between the base plate 20 and attaching plate 18, when the spike plate 19 is unattached therefrom.

The spike plate 19 may be provided with a plurality of headed studs 29 the shanks of which project upwardly substantially the thickness of metal comprising the attaching plate 18, enabling the shanks to pass through slots 25 and the underside of the headed portions of studs 29 to engage the plate 18 for securely holding the spike plate 19 thereto. Said spike plate is applied in such manner that the headed studs are inserted first into the rounded or enlarged openings of the slotted openings or key-slots 25, and upon engaging the underside of the metal spring 28, the studs bow the spring, after which the shanks register with the smaller parts of the slots 25 and then being pushed forwardly towards the forward end of the plate 18 or until the shanks of studs 29 have reached their limit of movement in the smaller ends of the slots.

To securely lock the spike plate 19 to the attaching plate 18 and prevent accidental removal of the spike plate 19 therefrom, I have provided on the underside of the said plate 19, a means which in practice engages with the opening 26 in the plate 18. Such means may conveniently be an elongated arm or flat spring member 30 and mounted at one end to the plate, as towards the forward part thereof by a rivet 31. Adjacent the end opposite from the rivet end is a detent 32 which for convenience protrudes upwardly and away from the spring arm 30 but is securely attached to the spring arm by being welded or otherwise held thereto. When spike plate 19 has been slid home upon attaching plate 18, that is, after the headed studs 29 have been inserted in and moved to the smaller ends of slots 25, detent 32 will then register with and enter opening 26 thereby preventing any possible dislodgment of the spike plate 19 from the plate 18. When desiring to remove

the spike plate from the plate 18, the spring arm 30 may conveniently be lifted at its free end away from the underside of the respective plates thereby removing the detent 32 from the opening 26, the arm may then be swung if desired, 5 slightly to either the left or right as shown in dotted lines of Figure 1, and in detail in Figure 8. The detent in such condition rests on the underside of the spike plate 19, after which the plate may, with slight pressure towards the rear, 10 be disengaged from the plate 18. When thus removed, the flat spring member 28 automatically snaps down against and closes the several openings 25 and 26.

It has been found that the usual construction 15 of spikes depending from spike plates of the prior art often bend or break when coming in contact with an obstruction in the ground, such as a stone, thereby rendering further service of the plate worthless. In the present invention, I 20 have provided the spikes 33 depending from plate 19 of a durable and sturdy construction both by utilization of tempered steel and by arching or reinforcing the same at the bends as at 34 and clearly appearing in section of Figure 10. 25 Said arching may be accomplished by utilization of a power press (not shown) in punching or stamping a portion of the material. From the foregoing it will be readily understood that the strength of the spikes 33 are materially enhanced 30 and the ability thereof to withstand wear and tear will be increased.

It further is to be understood, owing to the construction of the spike plate 19, that it will not be necessary to designate "rights" and "lefts" 35 since the structure shown enables the removable spike plate to be used for either the right or left shoe. Furthermore, should a spike become damaged, the user can remove the damaged plate and apply a new one without removing or changing his shoe. 40

Referring now more particularly to Figure 11, I have shown a slightly different construction of attaching plate 18 and different manner in which it may be made fast with respect to the base plate 20. In this respect, I have illustrated the attaching plate 18 as being flat, and in order to provide for the recess 24 as heretofore described, I have provided washers 35 (three in number) one at each corner, and means associated therewith for making said attaching plate with interposed washers fast to the base plate 20. One such means comprises rivets 36 passing through from the insole of the shoe and terminating at the outer surface of the attaching plate 18. 55 This construction permanently holds the immovable members together and to the shoe, assuring against wobbling or displacement. It is to be understood that in securing the aforementioned members to the shoe, the sole or heel are not affixed thereto until after the members are first set. The spike plate 19 with headed-studs 29 and stud 32 may be applied to the attaching plate 18 as heretofore described in detail. 60

I have shown a further modification of attaching plate and spike plate in Figures 12 to 14 inclusive. In this instance an attaching plate 37 may be secured to the under surface of either to the heel 16' or sole 17' of the shoe 15' by flat-head screws 38 countersunk in the plate so as not to interfere with attaching or removing spike plate 39 therefrom. Said plate 37 in this instance may be constructed so as to provide overhanging longitudinal shoulders 40 at its two side edges as seen in Figure 14. 65 70 75

The spike plate 39 may be constructed as heretofore providing spikes 41, but having its longitudinal side edges turned up and bent inwardly to provide grooves 42. Said grooves will engage 5 the shoulders 40 when the spike plate 39 is slid home upon attaching plate 37. In order to lock the spike plate 39 to the attaching plate 37 so as to prevent accidental displacement, I have shown an elongated spring arm 43 pivotally 10 mounted, as at 44, to the underside of the spike plate 39, free to move in a lateral direction when lifted at its free end. Said arm 43 adjacent its free end, that is, its end opposite to the pivoted end, is bent inwardly in the shape of a detent 15 45 and is adapted to pass through a slot 46 in the spike plate 39 and thence into a similar opening 47 in the attaching plate 39. In this condition the spike plate is prevented from sliding and is therefore held securely to the plate 37 and can- 20 not be removed until the spring arm with the 25 detent is released from the opening 47. When the detent is lifted clear of the said opening 47, the arm may be then swung laterally into a position illustrated by the dotted lines in Figure 12, whereupon the spike plate 39 may be easily slid 25 outwardly towards the forward end of the shoe 15' and removed.

I claim:

1. A shoe plate assembly comprising a plurality of attaching plates adapted to be permanently attached to the sole and/or heel portions of a shoe, one of said plates being adapted to be placed between the innersole and outer sole of the shoe and being provided with means for retaining a second one of said plates attached thereto, said second plate being designed to be positioned in the plane of the outer face of the outer sole, and said second plate being provided with means for holding a removable spike plate 40 thereto.

2. A shoe plate assembly comprising a plurality of attaching plates adapted to be permanently attached to the sole and/or heel portions of a shoe, one of said plates being adapted to be placed between the innersole and outersole of the shoe and being provided with means for retaining a second one of said plates attached thereto, said second plate being designed to be positioned in the plane of the outer face of the outer sole, 45 said second plate being provided with means for holding a removable spike plate thereto, and said second plate and spike plate having other means whereby the said respective plates are locked.

3. A shoe plate assembly comprising a plurality of attaching plates adapted to be permanently attached to the sole and/or heel portions of a shoe, one of said plates being adapted to be placed between the innersole and outersole of the shoe and being provided with means for re-

5 taining a second one of said plates attached thereto, said second plate being designed to be positioned in the plane of the outer face of the outer sole, said second plate being provided with means for holding a removable spike plate thereto, and said second plate and spike plate having other means whereby the said respective plates are locked together, said means comprising a hole and a detent whereby said detent will engage the hole preventing disengagement of the spike plate 10 from the second plate.

4. A shoe plate assembly comprising a plurality of attaching plates, one of said plates being adapted to be permanently placed between the inner sole and outer sole of a shoe, the second 15 one of said plates being attached to the first said plate and said second plate being designed to be positioned in the plane of the wearing surface of the outer sole and being provided with means for holding a removable spike plate thereto, and 20 spring pressure means in said second plate to lie contiguous to the first said means when the said spike plate is detached therefrom.

5. A shoe plate assembly comprising a plurality of attaching plates, one of said plates being 25 adapted to be permanently placed between the inner sole and outer sole of a shoe, a second one of said plates being provided with means for retaining it to the first one of said plates, said means comprising a plurality of offset corners and rivets 30 applied therethrough and through the first named plate thereby securely attaching together the said plates, said second plate being provided with means for holding a removable spike plate thereto, said spike plate having means at a part 35 thereof for engaging a registering part of the second plate whereby the spike plate is prevented from accidentally becoming dislodged.

6. A shoe plate assembly comprising a plurality of attaching plates, one of said plates being 40 adapted to be permanently placed between the inner sole and outer sole of a shoe, a second one of said plates being provided with means for retaining it to the first one of said plates, said means comprising a plurality of offset corners 45 and rivets applied therethrough and through the first named plate thereby securely attaching together the said plates, said second plate being designed to be positioned in the plane of the wearing surface of the outer sole and provided 50 with means for holding thereto a removable spike plate having arched spikes, and said second plate being provided with means juxtaposed against the inner surface thereof and adapted to lie contiguous to the first said means when the said spike plate is detached therefrom thereby preventing dirt and the like entering through said first means.

ABRAHAM SCHEMEL.
